SUPPORTING POLE FOR ELECTRICAL CONDUCTORS

Application filed April 25, 1928. Serial No. 272,841.

This invention relates to improvements in manufactured structures for supporting electrical wires such as poles, towers, cross-arms and suspension insulators.

5 The object of the invention is to improve such structures by constructing them in such a manner that a substantial amount of electrical insulation is introduced between those portions thereof which are adjacent to the 10 electrical conductors and those portions which are in electrical contact with or near to the earth or which are in the electrical path between the conductor and the earth.

The invention comprises the types of construction described and claimed hereinafter in connection with the drawings and equivalents thereof, of which

Fig. 1 is a front elevation of a hollow pole, consisting of three sections and having insulating blocks interposed between the sections and having tension members terminating at the insulating blocks.

Fig. 2 is a horizontal cross section taken at 2—2 of Fig. 1.

25 Fig. 3 is a vertical cross section between 1—1 and 2—2 of Fig. 1 and on the center line 3—3 of Fig. 2.

Fig. 4 is a front elevation of a three section hollow pole with insulating blocks between the sections and having the tension members equipped with strain insulators, the tension members being terminated at the ends of the complete assembly.

Fig. 5 is a horizontal cross section taken at 5—5 of Fig. 4.

Fig. 6 is a vertical cross section of the portion 2—2, 3—3 of Fig. 4, on the center line 6—6 of Fig. 5.

Fig. 7 is a portion of a pole in which the exterior members are of metal of sufficient thickness to be self supporting and having insulating blocks between the sections and means for attaching the adjacent portions of the pole to the insulating blocks, a portion of the pole being cut away to show the fastening.

Fig. 8 is a vertical cross section of Fig. 7 taken thru the center of the pole.

Fig. 9 is a front elevation of a portion of a 50 two section pole in which the bottom portion

is of insulating material and the top portion of steel, the tension members being equipped with insulators and attached to plates at the top and bottom of the pole. There is no insulating block between the sections of the pole.

Fig. 10 is a structure of suitable form for use as a cross-arm or as a suspension line insulator. The exterior member is of insulating material and the tension member is provided with insulating sections, a portion of the exterior member being cut away to show an insulating section.

Fig. 11 is a vertical cross section thru the center of a structure suitable for use as a suspension line insulator, both the exterior compression member and the interior tension member being of insulating material, the balance of the hollow interior being filled with insulating or arc quenching liquid.

Fig. 12 illustrates the method of using the structure of Fig. 10 as a cross-arm and the structure of Fig. 11 as a suspension insulator, a steel tower being shown for illustrating purposes only.

In recent years the use of wood poles and cross-arms for the support of electrical wires and cables for the transmission of electrical energy has been on the decrease, due not only to the fact that wood poles are becoming increasingly expensive, but because it is difficult to secure poles of sufficient height and strength for use in connection with present day high tension systems. Tubular metal poles and poles constructed of concrete and other types of metal poles and structures are now being employed for supporting high tension wires.

High tension wires must be insulated from each other, and from the earth, and the major problem is to insulate them from the earth. For instance, if there is a potential of 100,000 volts between two conductors and between those conductors and the earth, it is necessary to provide for each conductor an individual insulator having an insulating value suitable for a potential of 100,000 volts, whereas the conductors would be sufficiently insulated from each other if each were equipped with an insulator suitable for a potential of 50,000

volts, since the two insulators are in series with respect to the potential between the two wires. Furthermore, there are other factors, such as induced voltages caused by lightning, etc., which still further increases the potential between the conductors and the earth without increasing the potential between conductors.

An individual pole or structure may support many conductors, let us say, for instance, 10 nine conductors having a potential of 100,000 volts between conductors. It is more or less apparent that if the nine conductors are each supported on a 50,000 volt insulator, and in addition a 50,000 volt insulator is installed 15 in the pole or structure itself, between the lower portion of the pole and the upper portion to which the conductors are attached, substantially the same amount of insulation between conductors and earth is provided as 20 will be provided if each individual conductor is equipped with a 100,000 volt insulator, the insulator supports being uninsulated from the earth.

The benefits derived from insulating the 25 upper portion of a pole or tower supporting high tension conductors is by no means limited to the saving in the total amount of insulation required, as outlined above, but such construction makes it feasible to greatly reduce 30 the maximum strain upon the insulators resulting from lightning disturbances, this result being accomplished by the use of so called "counter potential wires" in a manner and by methods known to the art. Also, by means 35 of properly arranged construction workmen are enabled to work upon conductors which are alive, either intentionally or otherwise, with relative safety as compared with working on a conductive type of pole or structure.

Heretofore the only construction used to bring about the desired result has been of a temporary nature consisting of replacing some of the metal members of a transmission 45 line tower with wood timbers, the wood members being both in compression and tension, and the use of wooden cross-arms on steel towers.

My invention relates to a structure more particularly adapted for use as a pole for 50 systems where poles of medium lengths and strengths may be used to advantage although my construction may, with slight modifications, be used for insulating different portions of a steel transmission line tower. My structure may also be adapted for use as a cross-arm or as a suspension type insulator.

In Fig. 11, C is a hollow, outer compression member of insulating material, such as porcelain, fitted with end plates PP, and having 55 tension insulators as SI inside the compression member C. Since the insulator SI is entirely enclosed its surface is normally dry, but the insulating qualities of the inner insulator SI may be greatly improved by filling 60 the balance of the space with insulating oil

or other suitable liquid as L. In some cases it may not be economically sound to provide sufficient insulation to prevent a flashover of the interior insulator under certain voltage conditions but it may be desirable to quench 70 the arc quickly and for such a purpose arc quenching material, such as carbon tetrachloride may be used in place of oil. When used as a suspension insulator the load is carried entirely by the tension member SI, and the exterior member C may be made relatively 75 light and inexpensive.

Fig. 10 shows a type of construction adapted to be used as a cross-arm as shown at CA, Fig. 12. There are several materials 80 from which the member C may be made such as commercial fiber, special compositions consisting of wood pulp, asbestos fiber, etc., compounded and impregnated with asphaltic or 85 bituminous compounds, or mixed with Portland or other cement. The strain insulator SI may be of wood or other suitable material, and as many may be used in series as may be desirable for any particular length of arm, or any particular flashover voltage. The plates PP may be of any suitable material of 90 sufficient strength, and need not be of insulating character. The tension member is placed in tension by tightening the nut N which is threaded on the tension rod T. An 95 insert block IN may be provided to facilitate attaching the cross-arm to a pole or tower.

Fig. 12 shows a cross-arm, CA, of this construction applied to a steel tower ST, with a suspension insulator U of the form shown in 100 Fig. 11 attached to a cross-arm CA. It will be noted that the leakage distance over the insulator and along the cross-arm is greater than the shortest distance from the wire to the steel tower. The leakage distance along 105 the tension members in the insulator and the cross-arm, is less than the distance over the outer surface, but the inner insulators are always dry, and if necessary may be immersed in oil, thus making it possible to so design 110 structures that the effective flashover voltage will be the same for the interior and exterior paths.

If the insulating members SI are omitted from the tension member in Fig. 10, the insulating properties of the cross-arm will be considerably reduced but the structure will be considerably cheaper than, and will compare favorably with, wood cross-arms with respect to insulation, first cost and depreciation.

Fig. 1 is a pole consisting of three sections, P1, P2 and P3. The outer compression member may be metal tubing, or may be constructed of other materials or compositions 115 either conducting or non-conducting. Insulating blocks A—A are placed between the sections, metal plate TP is placed at the top and another plate BP at the bottom. Metal plates MP, Fig. 3, are placed on either side of 120

the insulator A, and the interior tension members T, of both the abutting sections, pass thru the insulating block A, and thru the metal plates MP, and are provided with a head or nut N on the outside of the metal plate. With this construction the insulating block is under compression strain only, and the tension members of one section are insulated from the tension members of the adjacent section by proper positioning in the insulating block as shown in Fig. 2.

The tension members of P1 pass thru the top plate TP and the insulator A1 and when tightened up they place the outer member of P1 in compression. Similarly the outer member of P2 is placed in compression, and at the same time sections P1 and P2 are securely fastened together, and in like manner section P3 is placed in compression and securely fastened to section P2. Additional sections may be readily added to the bottom of the pole.

In the complete assembly each section is insulated from the adjoining section with respect to both the exterior and interior members and the top section is insulated from earth by the accumulative values of the insulating blocks A1, A2, etc.

In Figs. 4, 5 and 6 a construction is shown in which the tension members T are continuous from the top plate TP to the bottom plate BP, and in order that a conducting path will not be established from the top to the bottom of the pole it is necessary to insert strain insulators, as S1, Fig. 6, in the tension members T. The tension members T pass thru the insulating block A, and thru the metal plate MP, and are fitted with threaded couplings or long nuts, CN, on the outside, bearing against plate MP, the adjacent section of the tension member being likewise threaded into the coupling CN. By tightening the couplings CN, the respective sections of the pole are placed in tension, and by tightening the nuts N at the top and bottom of the pole, the entire assembly is placed in tension. This type of construction has an advantage over that shown in Fig. 1 as it requires fewer holes in insulator A, and the insulator is, therefore, cheaper to make and less liable to breakage. The tension members T may be provided with offsets or other spring devices as shown at SP Fig. 6 in order to provide for a slight amount of resiliency in the tension members.

Figs. 7 and 8 show a portion of a pole having a heavy metal exterior member which requires no tension members. The insulator A is fastened to the two adjacent sections P1 and P2 by means of bolts B, which pass thru the metal plates MP and insulator A and thru the fastening plate or flange F, which in turn is fastened to the exterior metal member by means of suitable bolts H passing thru the exterior of the pole and thru plate F.

It is not essential that the exterior member be of metal it being only necessary that it be self-supporting in the sense that it requires no tension members extending from end to end thereof.

Fig. 9 shows a pole of two sections, at least one of which, such as P1, is of insulating material. In this type of construction no insulating block is required between the sections, but an insulating section SI must be included in the tension members and a sufficient number should be used in series to give a total leakage distance which is properly proportioned to the leakage distance of the exterior insulator P1. Between the sections P1 and P2 a suitable metal collar as MC may be used to hold the two sections in proper alignment or a metal plate may be used and the tension members of portions P1 and P2 may be independently fastened to such a plate. It is not essential that the section P2 be of metal, but it may be of metal or it may be of non-conducting material.

I claim:

1. A pole, for supporting the outdoor electrical conductors of an electrical distribution system, which includes two or more exterior, hollow, compression members assembled end to end; insulating blocks between the compression members and extending into the interior of the pole; metal plates on the exposed ends of the two terminal compression members; tension members located inside the compression members, passing through the insulating blocks and attaching to the plates at either end of the assembly, each tension member containing an insulating portion located between the portions of the tension member which are attached to the respective end plates.

2. A pole, for supporting the outdoor electrical conductors of an electrical distribution system, which includes two or more exterior, hollow, compression members assembled end to end, at least one of said members being of insulating material; tension plates on the exposed ends of the two terminal members; tension members located in the interior of the pole and attached to the tension plates at each end of the pole; each tension member being provided with an insulating portion positioned between those portions of the tension member which are attached to the respective tension plates.

In testimony whereof I have signed my name to this specification.

RALPH C. ROE.
